UNITED STATES PATENT OFFICE

GEORGE D. WILKINSON, OF OAK PARK, ILLINOIS, ASSIGNOR TO CRIBBEN & SEXTON COMPANY, OF CHICAGO, ILLINOIS, A CORPORATION OF ILLINOIS

BROILER OVEN

Application filed February 23, 1927. Serial No. 170,210.

The present invention pertains especially to a broiler-oven for a gas range, or other range; and the primary object is to provide an improved broiler-oven of simple and 5 staunch construction having improved means for adjusting the broiler-pan to any desired height in the drawer.

The invention constitutes a modification of the invention described in my Patent No. 10 1,614,167, granted January 11, 1927.

The invention is illustrated in the accompanying drawings in its preferred embodiment as applied to a gas range. It will be understood, however, that the broiler-burner 15 may be a gas-burner, an oil burner, or an electric burner or heating element.

In the drawings—

Fig. 1 is a broken front elevational view of a gas range constructed in accordance with 20 the invention; Fig. 2, a broken plan sectional view taken as indicated at line 2—2 of Fig. 1, but showing the broiler-drawer withdrawn and the broiler-pan broken; Fig. 3, a plan sectional view of the broiler-drawer with cer- 25 tain parts removed; Fig. 4, a vertical sectional view taken as indicated at line 4 of Fig. 3; Fig. 5, a vertical sectional view taken as indicated at line 5 of Fig. 3; Fig. 6, a transverse sectional view taken as indicated at line 6 of 30 Fig. 3; Fig. 7, a broken detail sectional view taken as indicated at line 7 of Fig. 3; Fig. 8, a broken vertical sectional view taken as indicated at line 8—8 of Fig. 2; Fig. 9, a broken vertical sectional view on an enlarged scale 35 taken as indicated at line 9 of Fig. 3; Fig. 10, a transverse sectional view taken as indicated at line 10 of Fig. 9; Fig. 11, a plan sectional view of a broiler-oven embodying a modifica- 40 tion of the invention; Fig. 12, a vertical sectional view taken as indicated at line 12 of Fig. 11; Fig. 13, a front elevational view of the modification; and Fig. 14, a broken vertical sectional view taken as indicated at line 14 of Fig. 12.

45 In the construction illustrated in Figs. 1-10, A designates an oven-unit comprising an upper baking-oven A' and a lower broiler-oven A²; B, the cooking-top of the range; C, a broiler-drawer with which the compartment A² is equipped; and D, a broiler-burner

located in the upper portion of the broiler-compartment A².

The withdrawable broiler-drawer C houses a tray, or broiler-pan, C' which in the preferred construction illustrated is removably carried by a supporting element C² carried by 55 adjusting mechanism C³ which is equipped with an adjusting handle C⁴ disposed outside the broiler-drawer, preferably in front of the front end thereof, said front end constituting 60 a closure for the broiler-compartment.

The broiler-compartment A² may be constructed in any desired manner. As shown, it is provided with a front frame 1 which constitutes a portion of the front frame of the 65 oven-unit, the frame 1 being provided with an opening through which the broiler-drawer works. The frame preferably is provided with a recess, or rabbeted portion, 1^a which forms a countersink adapted to receive a marginal portion of the front end of the broiler-drawer when the structure is in closed condition. 70

The broiler-drawer C may be of any suitable construction. It is shown as comprising a bottom 2 equipped with upturned lateral flanges 2^a; a rear end 3; and a front end 4. These parts may be connected in any suitable manner. The front end of the drawer, as appears from Fig. 1, constitutes a closure for 75 the broiler-compartment of the range. It comprises a rectangular frame 4^a, an outer sheet-metal panel 4^b, and a lining panel 4^c.

The adjusting mechanism C³ which serves to adjust the height of the broiler-pan preferably comprises a pair of parallel bars 5 upon which the supporting-member C² is fastened, as by means of bolts 5^a, said bars having depending from their central portions lugs 5^b; a transverse supporting bar 6 disposed in the lower front portion of the broiler-drawer and firmly secured to the walls thereof; an upper pair of links 7 connected at their front ends by pivots 7^a with the member 6, and at their rear ends by pivots 7^b with the central portions of the bars 5; a lower pair of links 8 connected at their front ends, by pivots 8^a with the member 6 and at their rear ends, by pivots 8^b, with the lugs 5^b; a swinging frame, or lifting device 9, connected by pivots 9^a with 80 85 90 95 100

the member 6 and serving to actuate the links; and a traveling-nut 10 connected with a screw 11 actuated by a handle 11^a disposed in front of the lower member of the frame 4^a. The screw 11 has a shaft 11^b journaled at its front end in the frame-members 4^a and 6 and at its rear end in a lug 12 which rises from a reinforcing bar 12^a which is secured to the bottom 2 of the drawer, as by means of screw-bolts 12^b. The members 6 and 12^a serve as supporting means for the tray-adjusting mechanism. These members, obviously, may be rigidly connected together and secured to the bottom and front of the drawer C, in any desired manner. As illustrated in Fig. 4, the member 6 is connected by screws 13 with the lower member of the frame 4^a.

The member 6 is provided at its rear side with suitable lugs for supporting the pivots 20 7^a, 8^a and 9^a, as will be understood from Figs. 3 and 9. The swinging lifting-member 9 is provided at its rear end with lateral extensions 9^b which extend beneath the upper links 7. The links 7 are bent, or offset, downwardly near their front ends, as indicated at 7^c, the purpose being to provide sufficient clearance for the front portion of the supporting-plate, or pan C². The upper and lower links serve substantially as parallel links adapted to carry the member C² through a vertical path in the raising and lowering of said member.

The swinging-member 9 is equipped with a central web-portion 9^c which is provided 35 with an incline, or wedge, 9^d which is adapted to be engaged by the traveling-nut 10. Thus, the incline serves as a cam engaged by the nut; and as the nut travels forwardly (see Fig. 9), it serves to swing the member 40 9 to the dotted position and elevate the broiler-pan. When the screw is turned in the opposite direction, the nut travels rearwardly, and the lifting device and broiler-pan settle down under their own weight.

45 The broiler-drawer may be housed within the broiler-compartment, excepting for the front end of the drawer which serves as a closure for the broiler-compartment. When desired, the broiler-drawer may be drawn 50 outwardly to the position shown in Fig. 8 to enable the meat to be inspected, turned, or removed, as desired. The broiler-pan can be lifted readily from the supporting-member C².

55 The broiler-drawer may be mounted to slide with relation to the broiler-compartment, in any desired manner. In the illustration given, the drawer is equipped at opposite 60 sides of its lower portion with guide-members 14 which engage traveling guide-members, or slides, 15, which are capable of traveling in guides 16 with which the broiler-compartment A² is equipped at opposite sides 65 of its lower portion. The means for slidably

supporting the broiler-drawer may be of the construction illustrated in the above-mentioned patent.

The nut 10 comprises a block having a threaded bore engaging the screw 11. The upper edge of the block is provided, as shown in Fig. 10, with a slot 10^a which is engaged by the member 9^c of the swinging lifting-member 9. The block 10 is equipped at its lower edge with rollers 10^b adapted to travel on the bar 12^a.

The handle 11^a of the adjusting mechanism is secured to the front end of the shaft 11^b, and is outside the broiler-drawer. Thus, the handle is readily accessible, and remains sufficiently cool.

In the modification shown in Figs. 11-14, C⁵ designates a broiler-drawer equipped with a tray-supporting member C² carried by bars 5 and actuating-links 7 and 8, as described with reference to the construction shown in Figs. 1-10. Also, in the modification, there is employed a swinging lifting-member 9, as in the previously described construction. In the modification, the bottom 2 of the drawer is equipped with a transverse bar 17 which supports the central portion of a lever 18 which is pivotally connected with the bottom of the drawer, as indicated at 19. The front end of the lever 18 projects through a slot 20 with which the lower portion of the closure 4 is provided and affords a handle 18^a. The bottom of the slot 20 is provided with teeth 20^a to enable the lever to be positioned at any desired point. The lever is provided centrally with a cam, or wedge, 18^b upon which rides a small roller 21 with which the swinging lifting device 9 is equipped. When the lever is swung in the direction indicated by the arrow in Fig. 11, the wedge serves to swing the member 9 upwardly and lift the pan C². When the lever is swung in the reverse direction, the pan and supporting mechanism is lowered by gravity.

In each of the described constructions, the tray-supporting member C² is carried by a parallel link-mechanism equipped with bars which support the member. This is the preferred construction, but any suitable tray-adjusting mechanism equipped with an exterior operating handle may be substituted without departure from the invention.

The foregoing detailed description has been given for clearness of understanding only, and no unnecessary limitations should be understood therefrom, but the appended claims should be construed as broadly as permissible, in view of the prior art.

What I regard as new, and desire to secure by Letters Patent, is:

1. In combination, a broiler-drawer, link-mechanism mounted therein and equipped with means for supporting a broiler-element, actuating means for said link-mechanism, said actuating means comprising a swinging-

member adapted to lift the link-mechanism, and means for actuating said swinging-member having an actuating handle disposed exteriorly at the lower front portion of the 5 drawer.

2. In combination, a broiler-drawer, adjusting-mechanism comprising links pivotally connected with the front end-portion of said drawer, a broiler-element supporting device 10 mounted on the rear ends of said links, and means for actuating said links, including a screw-rod journalled in the lower portion of said drawer and equipped with an exterior operating handle, and a nut actuated 15 by said screw-rod.

3. In combination, a broiler-drawer equipped with a front end adapted to form a closure for a broiler-compartment, links pivotally connected with said drawer adjacent 20 the front end thereof, means mounted on the rear ends of said links for supporting a broiler-element, and means for actuating said links, including a device extending through the lower portion of said closure and equipped 25

exteriorly with an operating-member.

4. In combination, a broiler-drawer equipped with a front end adapted to form a closure for a broiler-compartment, link-supporting means connected with said front end, 30 upper and lower sets of links having their front ends pivotally connected with said support, a broiler-element having pivotal connections with the rear ends of said links, a member disposed beneath and adapted to actuate said links, and a wedge device co-acting with said member and equipped with actuating means extending through the lower portion of said closure.

5. In combination, a broiler-drawer 40 equipped with a front end adapted to form a closure for a broiler-compartment, link-supporting means connected with said front end, upper and lower sets of links having their front ends pivotally connected with said support, a broiler-element having pivotal 45 connections with the rear ends of said links, a vertically swinging lifting member pivotally connected with the front end portion of said drawer and adapted to actuate said links, a screw-shaft journalled in the lower part of 50 said closure and equipped externally with actuating means, and a nut engaging said screw-shaft and having cam connections with said lifting member.

55 6. In combination, a broiler-drawer equipped with a hollow front end adapted to form a closure for a broiler-compartment, a mounting-plate housed within the lower portion of said closure, links pivotally connected 60 with said plate and extending rearwardly through the rear wall of the closure, a broiler-element support mounted on the rear ends of said links, a swinging lifting member pivotally connected with said mounting-plate 65 and adapted to actuate said links, a wedge de-

vice for actuating said lifting member, and actuating means for said wedge device extending through the lower portion of said closure and equipped with an exterior handle.

7. In combination, a broiler-drawer having a front end adapted to serve as a closure 70 for a broiler-compartment, link adjusting mechanism mounted in the lower portion of said drawer and equipped with means for supporting a broiler-element, and actuating means for said link-mechanism, said actuating means including a swinging member adapted to lift said link-mechanism.

75 8. In combination, a broiler-drawer having a front end adapted to serve as a closure for a broiler-compartment, link adjusting mechanism mounted in the lower portion of said drawer and equipped with means for supporting a broiler-element, and actuating means for said link-mechanism, said means including a yoke pivotally mounted on the 80 front end of said broiler-drawer, and a wedge device serving to lift said yoke against said link-mechanism.

90 9. In combination with a broiler compartment of a range, a drawer withdrawably mounted in said compartment and equipped with a front end adapted to form a closure for said compartment, a broiler tray, adjusting mechanism supported in said drawer and adapted to raise and lower said tray, link means connected to said adjusting mechanism and to a wall of said drawer for guiding said tray in a vertical path, and actuating means for said adjusting mechanism extending 95 through the front end of said drawer.

100 10. In combination with a broiler compartment of a range, a drawer withdrawably mounted in said compartment and equipped with a front end adapted to form a closure 105 for said compartment, a broiler tray, adjusting mechanism supported in the base of said drawer and adapted to raise and lower said tray, said mechanism being accessible from the sides of said drawer, link means connected to said adjusting mechanism and to a wall of said drawer for guiding said tray in a vertical path, and actuating means for the adjusting mechanism extending through the front end of said drawer.

115 11. In combination with a broiler compartment of a range, a drawer withdrawably mounted in said compartment and equipped with a front end adapted to form a closure for said compartment, a broiler tray, adjusting mechanism in said drawer and adapted to raise and lower said tray, link means associated with a wall of said drawer and connected to said adjusting mechanism for guiding said tray in a vertical path, and actuating means for said adjusting mechanism extending through the front end of said drawer.

GEORGE D. WILKINSON.
